UNITED STATES PATENT OFFICE.

FREDERICK MOENCH, OF WINNEBAGO, MINNESOTA.

HUMIDIFIER FOR CARBURETORS.

Application filed September 17, 1923. Serial No. 663,270.

To all whom it may concern:

Be it known that I, FREDERICK MOENCH, a citizen of the United States, and a resident of Winnebago, in the county of Faribault and State of Minnesota, have invented certain new and useful Improvements in a Humidifier for Carburetors, of which the following is a full, clear, and exact description, such as will enable others skilled in the art to make and use the same.

My invention relates to internal combustion engines and more particularly to means for humidifying or moistening the air which is mixed with the gasoline to provide the fuel to be fed to the cylinders of the engine.

Divers means heretofore have been devised for moistening this gaseous mixture, some of which have more or less accomplished the function for which they were designed, and in many instances a perceptible increase in the efficiency of the motor has been noted. In most instances, however, it has been the practice to withdraw steam or hot moist air from the radiator or some similar place and discharge the same into the gaseous mixture already formed as it passes from the carburetor to the engine cylinders, usually by providing an aperture in the engine intake manifold and connecting the steam feed pipe thereto. It is obvious that any foreign matter that might be in the water or radiator is very liable to and often does clog this feed pipe, and these substances also may be conveyed to the engine cylinders from which it could not be easily removed or dislodged and would in time damage the cylinders or pistons, or both.

In designing my device I have made provision for preventing foreign matter entering the fuel system and have installed the structure in such manner that the air being fed to the carburetor is humidified before it is mixed with the vaporized gasoline in the carburetor. I also feed the moisture, usually water, to the point of discharge in the air intake pipe by capillarity and lead the water by a suitable wick from the reservoir and pass the wick through said pipe so that the air drawn through the latter will take up the moisture as it rushes past the wet wick and thus become humidified.

In this manner the foreign particles that may be in the water will not be dislodged into the air pipe as they cannot be actuated or elevated by capillarity, and in order to prevent lint or pieces of the wick being thrown off I protect the latter with a fine mesh wire screen or the like. If desired, a suitable anti-carbon solution may be mixed with the water so that small quantities of the same is being constantly fed to the cylinders during the operation of the carburetor.

The divers objects of my invention reside in providing a humidifier that is extremely simple in construction so that it will be inexpensive to fabricate and can therefore be retailed for a moderate price; that is a unitary structure and may be readily installed by unskilled persons without the use of special tools; that is dependable and efficient in operation; and which has no moving parts to get out of order.

I prefer to carry out my invention and accomplish the foregoing and other objects by means of the structure hereinafter fully described and as more particularly pointed out in the claims, reference being had to the accompanying drawings that form a part of this specification, in which:

Figure 1 is a side elevation of an internal combustion engine of a well-known type showing the application of my humidifier thereto.

Fig. 2 is a horizontal section of my humidifier drawn full-size and showing the manner of attaching the same to the air intake pipe that leads to the carburetor.

Fig. 3 is a vertical section of the structure illustrated in Fig. 2.

Referring to the drawings, that illustrate a typical or preferred embodiment of my invention, I have designated similar parts by the same reference characters wherever said parts occur throughout the several views.

Figure 1 illustrates schematically a side elevation of a typical internal combustion engine, the engine block or casing being identified by the numeral 5, the exhaust manifold by the numeral 6, the carburetor by the numeral 7, and the intake or feed manifold by the numeral 8, the latter lead-

ing from the discharge stub of the carburetor to the respective cylinders of the engine. The air intake pipe 10 discharges into the stub 11 of the carburetor opposite the discharge stub 9 and its upper portion is enlarged and formed into a hood 12 that surrounds a portion of the exhaust manifold 6 and is spaced therefrom to permit air to enter therebetween in the direction of the arrows. The temperature of this air is raised by its contact with the adjacent parts of the engine and the exhaust manifold and is heated before it passes from pipe 10 into the carburetor.

15 My humidifier comprises a suitably shaped reservoir 13 elongated vertically and preferably of rectangular shape except that one of its vertical walls may be formed concave as shown at 14 in the drawings so that 20 it will conform to the contour of the air intake pipe 10 to which it is secured and with which it preferably contacts. The top wall of the reservoir is provided with an aperture and feed spout 15 that is threaded to receive 25 a removable closure cap 16. When the reservoir is positioned against the pipe 10 as illustrated it is held in place by a clamping band or strap 17 that surrounds the same about midway its height and partially encircles the pipe 10. Said band or strap 17 has laterally bent ends or ears 18 that are apertured to receive the shank of a bolt 19 which is held in place by a nut 20 so that 30 the lateral ends or ears 18 may be drawn towards each other to firmly clamp the reservoir 13 to the pipe 10.

The wall 14 next the pipe 10 is provided 40 with a hole 21 through which a wick 22 is passed, said wick being of any suitable material that will readily lend itself to feed the fluid in the reservoir by capillarity and it is long enough to extend to the bottom of the reservoir at its inner end and across the pipe 10 at its opposite or outer end. Preferably 45 alining apertures 23 and 24 are made in the pipe 10 diametrically opposite each other, the aperture 23 registering with the hole 21 in the reservoir, and the wick 22 passes through aperture 23 and then across the interior of the pipe to the opposite aperture 24 where its end is secured in any suitable manner. For the purpose of slightly compacting the wick where it is positioned in the pipe 10, I surround the same with a suitable wire gauze or wire mesh 25, or other reticulated element, which prevents pieces 55 of lint or portions of the wick being drawn off into the pipe 10 by the air which rushes past the same.

60 Thus it will be seen that when water or other liquid is placed in the reservoir the capillarity of the wick carries the same into the pipe 10 across the path of the air being fed to the carburetor and the air takes up the moisture and carries it into the carbure-

tor where the humidified air is mixed with the vaporized gasoline and creates a more efficient mixture of fuel for the engine. It will be obvious, however, that divers changes or modifications of the structure I have 70 herein shown and described may be made without departing from the principle of my invention. I therefore desire it understood that all such changes or modifications are fully contemplated as coming within the 75 scope of the appended claims.

What I claim as new is:—

1. A humidifier for carburetors comprising an apertured air intake pipe for the carburetor, an apertured liquid containing reservoir adjacent said pipe, and a wick one end thereof immersed in the liquid in said reservoir and the opposite end passes transversely through said pipe. 80

2. The combination with a carburetor and air intake pipe therefor, said pipe having an aperture, of a fluid container contiguous said pipe having an aperture adjacent the aperture in said pipe, and a wick immersed in the fluid in said reservoir and extending 90 therefrom through the apertures in said container and pipe and across said pipe whereby the moisture therefrom humidifies the air passing through the latter. 95

3. A humidifier for carburetors comprising an air intake pipe, a liquid reservoir having a concave wall fitting against said pipe, said wall and said pipe respectively provided with registering apertures, and a wick in said reservoir a portion of which is 100 passed through said apertures and extends transversely through said pipe. 105

4. A humidifier for carburetors comprising an air intake pipe, a liquid reservoir having a concave wall fitting against said pipe, said wall and said pipe respectively provided with registering apertures, a wick in said reservoir a portion of which passes through said apertures and extends transversely through said pipe, and a reticulated element within said pipe and surrounding said wick whereby to prevent solid matter from said wick and reservoir passing through said pipe. 110

5. A humidifier for carburetors comprising a reservoir having an apertured wall, and a wick immersed in the liquid contained in said reservoir and extended out through the apertured wall, said extended end of said wick passing through the air intake pipe 115 of the carburetor. 120

6. A humidifier for carburetors comprising a reservoir having an apertured wall, a wick immersed in the liquid in said reservoir and extended out through the apertured wall, and a reticulated element surrounding the outer portion of said wick the said element and the portion of the wick surrounded thereby being extended through the air-intake pipe of the carburetor. 125 130

7. A humidifier for carburetors comprising a reservoir having an apertured wall, a wick surrounded by a woven wire fabric, thereby compacting the outer portion thereof, immersed in the liquid in said reservoir and extended out through the apertured wall.

Signed at Brownsdale, county of Mower and State of Minnesota, this 10th day of August, 1923.

FREDERICK MOENCH.
